UNITED STATES PATENT OFFICE.

PERCIVAL STERN, OF NEW ORLEANS, LOUISIANA.

MEANS FOR STARTING INTERNAL-COMBUSTION ENGINES.

1,242,258.

Specification of Letters Patent. Patented Oct. 9, 1917.

Application filed October 26, 1914. Serial No. 868,577.

To all whom it may concern:

Be it known that I, PERCIVAL STERN, a citizen of the United States, residing at New Orleans, parish of Orleans, and State of Louisiana, have invented a certain new and useful Means for Starting Internal-Combustion Engines, of which the following is a specification.

This invention is a means for starting internal combustion engines, the same being useful particularly in cold weather.

It is well known that difficulty is experienced in starting into operation engines of the internal combustion type, more especially in cold weather. This is due, mainly, to the fact that the gasolene is in such a cold condition that it does not mix well with air, nor will it ignite readily within the cylinders.

As a remedy for this condition, it is proposed to heat the liquid combustible and to convert the same into a vapor by the aid of a special appliance used in conjunction with the intake manifold or by an appliance interposed in the gas line leading to the carbureter, such special appliance in either form being electrically heated.

Accordingly, the broad feature of this invention consists of an electrically heated device into contact with which the liquid combustible is caused to flow for the purpose of converting such liquid combustible unmixed with air into an explosive vapor, the latter being subsequently mixed with air and thereafter supplied to the engine cylinders under such conditions as to ignite at once when the engine is turned over or cranked, whereby the engine may be started into operation without priming the cylinders through the priming cocks as ordinarily practised, or requiring the operator to continuously hand crank the engine, or involving delay and annoyance in starting the engine by the operation of the self starters, so called.

According to one specific embodiment of the invention, I employ a plug attached, preferably, to the intake manifold, said plug being provided with an incased electrical resistance coil. Said coil is grounded at one end in the plug attached to the engine, but the winding is insulated electrically by mica from the plug. To this winding is attached a conductor leading to a switch (push button) from which a conductor extends to a

source of electrical energy, usually a battery of one form or another, and from said battery extends a conductor grounded in the engine, whereby the operation of the switch closes an electric circuit between the battery and the coil for the purpose of supplying current to said coil for heating the latter to the required temperature in a few minutes of time. The liquid combustible, usually gasolene, is supplied to the heating plug by a pipe leading preferably from a valved priming plug or from a separate tank, such liquid combustible being conducted into direct contact with the heated coil, whereby the liquid is converted into a highly explosive vapor adapted to be thereafter mixed with air and to be supplied at once to the cylinders for ignition therein when the engine is cranked.

Other features of the invention and the advantages thereof will be apparent from the following detailed description.

In the drawings,

Figure 1 is a diagrammatic view of my means for vaporizing a liquid combustible to be used in starting an internal combustion engine.

Fig. 2 is an enlarged sectional view through the electrically heated plug.

In the constructional form illustrated in Figs. 1 and 2, A is a metal plug within which is incased a resistance coil or winding B and to which is connected a feed pipe C for supplying from an available source a liquid combustible to said coil or winding B. The plug is shown as having a reduced and threaded end portion *a* and a longitudinal bore *a'*, the latter being reduced in diameter at one end so as to result in an aperture at one end portion of said plug. Within this longitudinal bore *a'* is positioned a tube or sleeve D composed of insulating material, such as mica, and coöperating with said sleeve or tube is the resistance winding B in such relation to the sleeve as to be insulated electrically thereby from the metal plug A. The winding is somewhat shorter than the plug so that said winding extends for a part of the length only of the plug, one end portion of said winding being mechanically attached to the plug whereas the other end portion of the winding is attached to a binding post E. Said post extends through the aperture in the end portion of the plug, from which said post is insulated by wash-

ers *e*, and a short sleeve *e'*, preferably of mica.

The plug is mechanically attached to a part of the engine, preferably to the intake manifold *F* thereof. A hole is tapped in the manifold at a suitable point, and into this hole is screwed the threaded end portion *a* of the plug.

The liquid combustible, usually gasoline, is supplied to the resistance coil so as to flow into direct contact therewith, whereby the heated coil vaporizes said liquid, *i. e.*, converts it into a highly volatile vapor. The conversion of the liquid combustible into vapor takes place in a chamber free from communication with air, so that the conversion takes place under such conditions that atmospheric air is not mixed with the vapor simultaneously with its production, it being observed that the liquid combustible is led into contact with the coil positioned within a closed chamber, thus precluding a destructive explosion in case of a back-fire. Subsequent to vaporization of the liquid, the vapor flows into the manifold so as to mix with air usually present in said manifold and thereafter the mixture is drawn into the cylinders when the engine is turned over, whereby the vapor is adapted to be exploded by a spark from the usual spark plugs so as to start the engine promptly in cold weather.

The liquid combustible is fed through pipe *C* independent of the gas line from the tank to the carbureter. In the case of automobile engines, the pipe *C* leads from the plug *A* to and through the dash, said pipe being associated with suitable means for feeding the liquid combustible. As shown, the pipe is attached to a priming cock *G*, the latter being provided with a cup and with a plug valve as usual, whereby a small quantity of gasoline may be poured into the priming cup and, with the valve opened, the liquid finds its way through the feed pipe to the plug *A* so as to flow into direct contact with the heated resistance winding, it being understood that said feed pipe is attached to said plug *A* for feeding the liquid combustible interiorly of the plug and to said resistance winding. If desired, a tank may be positioned on the dash and above the priming cock *G* for holding a limited supply of the liquid combustible so as to render the same available instantly for feeding the liquid to the vaporizer.

From the binding post *E* a conductor *h* leads to a switch *H*, the same being shown as a push button positioned on the dash, and from said switch a conductor *h'* leads to a source of electrical energy, such as a battery *I*, from which a conductor *i* leads to the engine so as to be grounded therein.

The operation is simple and readily apparent from the description. A small quantity of gasoline is introduced into the prim-

ing cup *G*, either from a small tank or any other available source, the cock being closed. The operator adjusts the switch *H* for closing the circuit so that current flows from battery *I* into and through the coil or winding *B*, heating the latter in a few minutes' time to the required temperature, after which the switch is opened. The priming cock is now opened for the liquid combustible to flow by gravity through the feed pipe, into the plug *A* and into direct contact with the hot resistance winding, the result of which is to convert the liquid into vapor, the latter flowing into the manifold and mixing with the air present therein, thereby producing a highly volatile vapor which is supplied to the cylinders. By turning the engine over, the vapor is drawn into the cylinders and ignited by the spark plugs, thereby starting the engine within a few minutes during cold weather and with practically no labor on the part of the operator.

When the device is not used for starting the engine, it may be utilized during the operation of said engine for feeding additional air to the gaseous mixture flowing from the carbureter through the intake manifold to the cylinders. By opening the priming cock *G*, air will be drawn through the pipe *C* into the intake manifold so as to mix with the gaseous mixture supplied thereto by the carbureter, thus incorporating additional quantities of oxygen into the mixture and increasing the combustible properties of such mixture.

This invention performs several important functions in the starting of an internal combustion engine and in the operation thereof. As has been stated, the invention operates as an electrically controlled vaporizer and as a primer in starting the engine, and by feeding air through the priming cock so as to mix additional air with the gaseous mixture supplied by the carbureter the combustible properties of the mixture are increased, thus making provision for increasing the speed of the engine and effecting substantial economy in the combustible liquid. In addition to the foregoing functions, the priming cock may be opened for introducing liquid other than the liquid combustible, thus permitting the operator to introduce water which is converted into a vapor which acts as a decarbonizing agent within the cylinders and other parts of the engine. Furthermore, the device may, under some conditions, be used independently of or in connection with the ordinary carbureter to the end that the engine may be run in a manner to test the carbureter.

Having thus fully described the invention, what I claim as new, and desire to secure by Letters Patent is:

1. The combination with an internal combustion engine, of starting means therefor

embodying a chambered member attached to the intake manifold of said engine, said chambered member being closed against the admission of atmospheric air thereto, an
 5 electrical resistance positioned within said chamber and exposed therein to the direct contact of a liquid combustible, means controllable at will for supplying electric current to said electrical resistance for heating
 10 the same independently of the heat developed by the operation of the engine, and means controllable at will and independent of the main fuel supply to the engine for feeding interiorly of said chambered member a liquid combustible which is free to flow into direct contact with said electrical resistance, said chambered member being in communication with said engine manifold for the resulting vapor to flow into said
 15 20 manifold and to be mixed with air within the latter prior to admission to the engine cylinders.

2. The combination with an intake manifold of an internal combustion engine, of a starting device embodying a chambered member attached to said manifold at a point intermediate its intake and outlet, said chambered member being closed against the admission of atmospheric air thereto, a resistance coil positioned within said chambered member and exposed therein for the direct contact therewith of a liquid combustible, means controllable at will for supplying an electric current to the resistance coil for heating the latter to a temperature suitable to effect the vaporization of a liquid combustible, and means controllable at will and independent of the main fuel supply to the engine for feeding interiorly of said chambered member a liquid combustible which is free to flow into direct contact with said resistance coil whereby the liquid combustible is vaporized within said chambered member, the resulting vapor being free to flow out of the chambered member and into said manifold for admixture with air therein prior to admission to the engine cylinders.

3. The combination with an intake mani-

fold of an internal combustion engine, of a starting device embodying a chambered member one end portion of which is attached to said manifold at a point intermediate its intake and outlet, the other end portion of said chambered member being closed against the admission of atmospheric air thereto, a resistance coil positioned within the chambered member and exposed therein for free contact with a liquid combustible, a valved liquid pipe connected to said chambered member intermediate its ends for feeding to the interior of said chambered member a liquid combustible which is free to flow lengthwise of the chambered member and into direct contact with said electrical resistance, whereby the liquid combustible is vaporized within said member, and a priming cup independent of the main liquid supply to the engine for feeding a liquid combustible to said liquid pipe, said priming cup and the valved pipe affording means for feeding through the chambered member a medium other than a liquid combustible.

4. The combination with the manifold of an internal combustion engine, of a chambered plug attached to said intake manifold, an electrical resistance positioned within said chambered member and exposed therein for the direct contact of a liquid combustible therewith, means for feeding an electrical current at will to said electrical resistance, and a feed pipe provided with a priming cock, said feed pipe being attached to the chambered plug for feeding to the interior thereof a liquid combustible which is vaporized by contact with said electrical resistance and said feed pipe and priming cock being also operable at will for feeding air through said chambered plug to said manifold.

In testimony whereof I have signed my name to this specification in the presence of two subscribing witnesses.
